CLOTHES WRINGER

Filed Aug. 6, 1923

R. Hamilton

By Thorpe Gerard Atty's

UNITED STATES PATENT OFFICE.

BRUCE E. SIPE, OF KANSAS CITY, MISSOURI.

CLOTHES WRINGER.

Application filed August 6, 1923. Serial No. 655,871.

To all whom it may concern:

Be it known that I, BRUCE E. SIPE, a citizen of the United States, and resident of Kansas City, county of Jackson, State of Missouri, have invented a certain new and useful Improvement in Clothes Wringers, of which the following is a complete specification.

This invention relates to clothes wringers of that class adapted for use on a power washing machine, and my object is to produce an efficient wringer provided with simple means for guarding against the winding of articles around the rolls or either of them, and with means whereby the wringer can be set in different positions or angles with respect to its support, for the convenience of the operator. Another object is to generally improve wringers of the class mentioned, as regards dependability of operation, durability, ease of control and inexpensiveness of manufacture.

With these objects in view the invention consists in certain novel and useful features of construction and combinations of parts as hereinafter described and claimed; and in order that it may be fully understood reference is to be had to the accompanying drawing, in which:—

30 Figure 1 is a side elevation of a wringer embodying the invention, and a part of the support of the wringer.

Figure 2 is a vertical section taken on the line II—II of Figure 1.

35 Figure 3 is a vertical section taken on the line III—III of Figure 2.

Figure 4 is a fragmental perspective view of one of the bearing blocks and the guard for the upper roll of the wringer.

40 Figure 5 is a detailed perspective view of one of the guards for the lower roll of the wringer.

Figure 6 is a detailed perspective view of one of the bearings for the lower roll.

45 Figure 7 is a vertical section of a part of the frame to disclose the drain table securing device, the table and certain other parts being omitted from the figure.

Figure 8 is a horizontal section on the line

50 VIII—VIII of Figure 7.

Referring now to the drawing, in which similar reference characters denote corresponding parts in all of the figures, 1 indicates a substantially rectangular up-right

55 frame having an internal channel extending

along its top and side, the frame comprising two similar sections fitting together side-wise and held in place by bolts or the like. The frame is secured at one end to a casting 2 mounted for horizontal swinging movement on a suitable support 3, the support being preferably a gear housing, and said support is provided with one or more notches 4 adapted for engagement by a locking-pin 5 mounted in depending portions of the frame, as at 6. A spring 7 is mounted on said rod and bears at its opposite ends against a collar 8 on the rod and one of the portions 6, and outward of the latter is provided with a handle 9 whereby the rod can be retracted from engagement with the notch 4 to permit the frame to be swung to the desired position and so secured by the spring-actuated locking-rod 5.

Secured in the lower end of the channel of the frame are a pair of bearing blocks 10 provided with suitable bearings 11 for the driven shaft 12, said shaft projecting into the casting 2 and being adapted for connection with gearing, not shown, for the operation of the wringer, it being understood that the special type of mechanism for driving the shaft 12 is unimportant in this connection and is therefore neither detailed in the drawing nor described. The shaft carries the usual wringer roller 13 and a gear-wheel 14 loosely intermeshed with a similar gear-wheel 15 on a second shaft 16, for the upper roller 17. The shaft 16 finds a bearing in fibre bearings 18 mounted in the lower ends of vertically slideable blocks 19 fitting in the channeled frame and capable of independent or conjoint upward or downward movement therein to accommodate the bulk of material passing between the wringer rollers. The blocks are provided with transverse grooves 20, in their upper ends and vertical notches 21 extending downward from said grooves. A guard

22 of substantially inverted U-shaped cross section, has end-tongues 23 fitting in the notches of said blocks and is adapted to prevent clothes from winding about the upper roll, and to prevent articles getting caught between the ends of the rolls and the frame

95 100

24 and 24^a for respectively overlapping the ends of rolls 17 and 13.

To serve as guards against the winding or wrapping of articles around the lower roll,

guards 25 fit against opposite sides of such roll and are pivotally suspended by arms 26 from sockets 27 formed on the sides of the frame, the said guards respectively functioning accordingly as the "wash" is passed through the wringer from one side or the other.

To hold the rolls yieldingly together with sufficient force for proper wringing action, the following mechanism is employed: An upwardly bowed spring 28 is engaged at its ends with the grooves 20 and overlies and closes the open upper ends of the notches 21 of said blocks 19, and a vertical screw 29 engages the spring at its center to apply downward pressure thereon. The screw is mounted in an arm 30 pivoted for vertical movement in the upper part of the frame. A lever 31 is also pivoted in the frame and overhangs the free end of the pivoted arm to hold the same depressed to operative position against the upward pressure of the spring, and a spring 32 bearing against said lever and the frame, is adapted to return the former to the position shown in Figures 1 and 2, after each depression thereof, it being understood that when said lever is depressed it permits the compressed spring 28 to throw the screw and pivoted arm upward and thus relax the pressure of the upper roll upon the lower roll.

A drain table 33 extends through the frame below the roll 13 and guards 25 and is adjustable to slope in one direction or the other. It has side channels 34 engaged by lugs 35 of bearing blocks 10, whereby its adjustment in one direction or the other is positively limited, and it is stabilized in one position or the other by resting on the bottom of the frame. To hold it against slippage through pressure applied tending to slide it on the bottom and lugs 35, it is provided with sets of depending teeth 36, one or the other of which being engaged with the underlying arm of a horizontal fork 37 fitting slidingly in one side portion of the frame, the channel 34 at the corresponding side of the table, receiving the other or at that time inoperative arm of the fork, as indicated by dotted lines in Figure 2. The table cannot rock on lugs 35 as rocking movement in one direction is prohibited by contact of the underside of the table with the bottom of the frame of the wringer, and in the other direction through engagement of a set of the teeth 36 with one of the tines 37 of the fork, the other tine as mentioned having no function to perform but being received within the channel of the table as otherwise it would interfere with the operation of its companion tine in engaging the teeth. The fork has a stem 38 extending through the frame, and provided with a handle 39, and a spring 40 fits around the stem and bears against the frame and fork to yieldingly ad-

vance the fork to the operative position described. A pull applied to the handle will retract the fork to permit the table to be adjusted to a reversed position and angle suitable for proper functioning when "wash" is passed through the wringer from the other side thereof. In this connection it will be noted that the spring-actuated table securing device described, cannot get out of operative position by rotative movement, as the arms of the fork fit in notches 41 formed in inturned flanges 42 of the frame. Said flanges are also notched at 43 to receive the side flanges 44 of the bearing blocks 10 for the proper support of the lower roll.

The operation of the wringer is obvious from the description of the function of the various parts, it being apparent that no oiling is necessary as the water expressed from the "wash" will serve for lubrication purposes. Prior to the assembly of the parts, however, the fiber bearing blocks are soaked in oil and thus promote ease of and quietness in operation.

From the above description it will be clear that I have produced a device of the character described, which embodies the features of advantage set forth, and which is susceptible of modification in minor particulars without departing from the spirit and scope of the appended claims.

I claim:

1. In a clothes wringer, a frame, a roller mounted in said frame, a pair of vertically sliding blocks in said frame above said roller and formed with bearings and above the latter with vertical notches, a second roller mounted for rotation in the bearings of said sliding blocks, a guard resting on said second roller and having its ends received within said notches of the blocks.

2. In a clothes wringer, a frame, a roller mounted in said frame, a pair of vertically sliding blocks in said frame above the roller and formed with bearings and above the latter with vertical notches and transverse grooves, a second roller mounted for rotation in the bearings of said blocks, a guard resting on said second roller and having its ends received within said notches, a spring fitted at its ends in the grooves of the blocks and overlying the vertical notches, and means for imposing pressure on said spring to apply yielding pressure on the sliding blocks to engage the second roller with the first roller.

3. In a clothes wringer, a frame, a lower roller mounted in said frame, a pair of vertically sliding blocks in said frame above the lower roller and formed with bearings and above the latter with vertical notches opening at their upper ends in transverse grooves, an upper roller mounted for rotation in the bearings of said bearing blocks, a guard resting on said upper roller and having its

ends received within said notches, a spring fitted at its ends in the grooves of the blocks and covering the upper open ends of the notches, and means for imposing pressure on said spring to apply yielding pressure on the sliding bearing blocks to engage the upper roller with the lower roller.

4. In a clothes wringer the combination of a frame having upright spaced channelled sides, bearings in the channelled sides, having inwardly-projecting lugs, a drain table extending through the frame and partially supported thereby when in operative position and provided with side channels engaged by said lugs, and at one side with depending teeth adjacent the ends of one of the channels, and spring-actuated means for engaging either of said teeth to cooperate with the said lugs and frame in holding

the table at the desired point of adjustment 20 and in tilted position.

5. In a clothes wringer, the combination with an upright frame having inwardly-projecting lugs, a drain table extending through the frame and partially supported thereby when in operative position and provided with side channels engaged by said lugs, spaced teeth depending from said drain table, and a spring-advanced fork mounted in one side of the frame, the tines of said fork being alternatively adapted to engage the teeth or the channel of said table according to the position of the latter and cooperate with the lug and frame in holding the table in position. 35

In witness whereof I hereunto affix my signature.

BRUCE E. SIPE.
